Company, Chicago, Ill., a corporation of Dela-
ware

Application April 19, 1939, Serial No. 268,786

12 Claims. (Cl. 84—1.19)

My invention relates broadly to synthetic electrical musical instruments employing a multiplicity of generators, and more particularly to those instruments where each generator originates several tone partials. The invention is particularly directed to instruments in which the generators require a steady exciting or polarizing potential.

One of the objects of my invention is to provide a circuit employing a multiplicity of generators and wherein a generator is required to produce several partials simultaneously, the output of the generator being the sum of the outputs taken individually.

Another object of my invention is to provide a circuit arrangement for a generator having means for applying all pitch and amplitude controls to the steady exciting potential of a generator, thus avoiding the expense and the high frequency losses involved in the shielding which is made necessary by applying these controls to tone-frequency circuits.

Another object of my invention is to facilitate control of attack and decay rates in an electrical musical instrument.

Still another object of my invention is to provide means for controlling the variation in harmonic content when the pitch is changed in a frequency responsive circuit.

A further object of my invention is to provide a circuit arrangement for an electrostatic generator system operating without harmonic generators above the range of fundamental frequencies generated and without producing sudden changes in harmonic content.

A still further object of my invention is to provide a circuit arrangement for an electrical musical instrument capable of inexpensive production on a quantity basis for producing a highly satisfactory synthetic instrument comprising a minimum number of operating parts.

Still another object of my invention is to provide a circuit arrangement for an electrical musical instrument employing a multiplicity of playing keys and in which the timbre is independent of the number of playing keys struck.

Another object of my invention is to provide a circuit arrangement for an electrical musical instrument in which the cumulative effects of a multiplicity of generators is obtained when striking a multiplicity of keys simultaneously.

A further object of my invention is to provide a circuit arrangement for a synthetic electrical musical instrument having additive circuits for cumulative association with the same generator

whereby amplitudes of the tones are integrated according to the number of keys struck while the quality of the tones remains uniform.

Other and further objects of my invention reside in the production of an additive harmonic control circuit for synthetic organs as set forth more fully in the specification hereinafter following by reference to the accompanying drawings in which:

Figure 1 schematically illustrates the control circuit of my invention in association with a single generator; Fig. 2 shows the equivalent circuit of the generator when producing a signal partial; Fig. 3 shows the equivalent circuit when several partials of different amplitudes are produced simultaneously; Figs. 4, 4a and 4b conjointly show the schematic circuit connections for a two manual electrostatic organ embodying the principles of my invention; Figs. 5 and 5a conjointly show schematic circuit connections for an electric organ embodying my invention and using only one contact for each playing key; and Fig. 6 shows a modified form of quality control for electric organs illustrating an arrangement of wave-filters in the amplifier circuit and without the individually connected tappet controlled switches.

My invention is directed particularly to an improved circuit arrangement for synthetic electric organs of the type which employs a multiplicity of electric alternators for generating the notes of a musical scale and their associated partial tones. It can be applied to the timbre-control arrangements of any one of several of such instruments previously known to the art. When properly applied to such an instrument, it will result in improved performance and in considerable simplification.

Instruments of this class have great flexibility and are capable of producing an almost limitless variety of musical effects. These great possibilities are not obtained without price; such instruments are inherently complicated and of necessity contain large numbers of electrical circuits. It is inevitable that preventing undesirable reactions among these circuits should be a difficult problem. Some of the pioneer workers in this field have made little attempt to solve it, merely indicating schematically how the partial tones are to be obtained and where applied, and, quite justifiably, leaving it to later inventors to work out control schemes whereby such reactions can be eliminated. Others have arrived at partial solutions, often at almost prohibitory expense in the way of auxiliary apparatus. My

invention aims at a complete solution of the reaction problem, together with a substantial reduction in the number of parts required, and without loss of useful flexibility. It also aims at 5 a musically satisfactory, controlled, and progressive change in timbre with pitch. Other aims will become apparent as the explanation proceeds.

Some of the requirements which must be fulfilled if the instrument is to be a worthy competitor of the pipe organ are as follows: (a) When any possible chord is struck, the timbre must not be noticeably different from the timbre of a single note. (b) With the volume control 10 left fixed, the volume emitted should be approximately proportional to the number of notes sounding simultaneously. (c) The timbre must not change abruptly in going from one note to another.

20 Requirements (a) and (b) are both precisely fulfilled if, when a chord is struck, the amplitude of each component is equal to the sum of the amplitudes of the like partials of the different notes composing the chord, when each is struck singly. 25 By "like partials" I mean to convey partials of different notes which agree in frequency. For example, the third harmonic of any C on the organ, the fourth harmonic of the G below the C, the second harmonic of the G above the C, and 30 the fundamental of the G which is an octave higher yet, are all "like partials" as they have the same frequency. Any system in which the amplitude of each component of a chord is equal to the sum of the like partials, is hereinafter 35 called an "additive system." Obviously, it is very desirable to have an additive system. The difficulty with requirement (c) generally arises near the high frequency end of the instrument's range. It is hard to justify providing high frequency generators which supply harmonics only, 40 particularly in view of the fact that such harmonics do not exist in present acoustical instruments and theoretically seem of little value. However, the dropping off of harmonics at the 45 high end of the register must be obtained without any sudden change of timbre.

It has been proposed heretofore to locate the necessary key switches and harmonics amplitude control elements in the output circuits of 50 the generators. Indeed, where electromagnetic alternators are employed, this is the only possible course, as reducing the field current of a magnetic alternator to zero does not reduce the output current to zero, hence control in the input circuit 55 cannot be used. This expedient makes it possible to work out an additive system rather readily, but as the output circuit carries audio frequency currents, new difficulties are introduced, to wit: (a) The large number of extensive circuits tend to 60 couple with each other, capacitively or inductively, and a very complete and hence bulky expensive system of shielding must be employed to eliminate spurious discordant notes. (b) This shielding involves losses in stray capacities and 65 eddy currents. (c) These losses are different for different pitches, thus complicating the "voicing" problem. (d) Condenser discharge methods of regulating attack and decay rates will not work on alternating currents, so that this convenient 70 device cannot be applied directly.

My invention provides an additive system which is applicable to the input circuits of electrostatic alternators, and hence does not incur any of these additional difficulties. It is also applicable to the 75 polarizing circuits of polarized photocells, and

hence also to photoelectric organs. For simplicity however, only the electrostatic application has been described. Fig. 1 shows the circuit connections to a single generator according to my invention. For purposes of explaining my invention 5 consider an instrument in which each generator is required to produce n partials, or less, in the case of the generators near the end of the fundamental pitch range of the instrument. These partials may all pertain to a single manual, or 10 some may belong to one manual and others to other manuals. In the case of electrostatic generators as illustrated herein, the alternating current output potential is proportional to the direct current input potential so that any relationships 15 derived for the input potential of the generators will also be true of the outputs. Therefore, only the input potential E_g will be considered. Two cases will be taken up. In case I all the resistors are equal, and in case II they are considered as 20 unequal, but may also be equal, so that case I is actually included under case II. It is taken up separately for simplicity of explanation.

Case I

$$R_1=R_2=R_3=\dots=R_n=(\text{say}) R$$

25

From Fig. 2, the generator input potential when a single partial is being generated is

$$E_g = E_x \frac{\frac{R}{n-1}}{\frac{R}{n-1} + R} = E_x \frac{R(n-1)}{R + R(n-1)} \quad 30$$

$$E_g = \frac{E_x}{n} \quad 35$$

35

where E_x is the potential to which potential-adjuster V_x corresponding to the given partial is adjusted.

From Fig. 3, the generator potential when a number of partials of different amplitudes are being generated simultaneously, is 40

$$E_g = \frac{R}{n-q} (i_1 + i_2 + \dots + i_m) \quad 40$$

where q = number of partials in use

i_x = current in R_x

$$E_1 = E_g + R i_1$$

$$E_2 = E_g + R i_2$$

$$E_m = E_g + R i_m$$

45

50

There will be q of these equations, all similar. Adding these q equations gives

$$(E_1 + E_2 + \dots + E_m) = q E_g + R (i_1 + i_2 + \dots + i_m) \quad 55$$

But

$$R (i_1 + i_2 + \dots + i_m) = (n-q) E_g$$

$$(E_1 + E_2 + \dots + E_m) = q E_g + (n-q) E_g = n E_g$$

$$E_g = \frac{E_1 + E_2 + \dots + E_m}{n} = \frac{E_1}{n} + \frac{E_2}{n} + \dots + \frac{E_m}{n} \quad 60$$

The generator voltages for these partials taken one at a time are

$$\frac{E_1}{n}, \frac{E_2}{n} \quad 65$$

65

etc., as was shown above.

The additive condition is therefore satisfied.

A numerical example of case I might be helpful at this point. Suppose that two manuals 70 were desired, each utilizing six partials. Then if the total polarizing potential available were 480 volts the maximum potential available for any one partial would be $480/12$ or 40 volts. While this seems rather small in the light of present 75

practice, it must be remembered that my system permits a great reduction in the capacitances in shunt with the generator outputs, and hence the generator output will be a larger fraction of the polarizing potential. If trouble is experienced in obtaining a sufficient number of millivolts output to blanket the noise due to the connection to the rotors and the internal amplifier noise, the generators can be divided into groups, each group supplying its own input tube. The shunt capacitance would thus be reduced still more. The input tubes could all work into a common amplifier. It will be noted later on that some help in this problem can be obtained by properly adjusting the resistors.

Case II

$$R_1 = \frac{R}{k_1}; R_2 = \frac{R}{k_2} \text{ --- in general } R_x = \frac{R}{k_x}$$

Let Σ indicate a summation which includes all circuit branches.

Σ' indicate a summation which includes all circuit branches connected to zero potential.

Σ'' indicate a summation which includes all circuit branches connected to a potential other than zero.

Then from Fig. 2 the potential for any single partial is

$$E_{ox} = \frac{E_x R'}{R_x + R'}$$

Where R' = effective resistance of the other $n-1$ resistors in parallel

$$= \frac{1}{\frac{R}{k_1} + \frac{R}{k_2} + \dots + \frac{1}{\frac{R}{k_{x-1}} + \frac{R}{k_{x+1}}} + \dots + \frac{1}{\frac{R}{k_n}}}$$

$$40 \quad R' = \frac{1}{\frac{k_1}{R} + \frac{k_2}{R} + \dots + \frac{k_{x-1}}{R} + \frac{k_{x+1}}{R} + \dots + \frac{k_n}{R}} = \frac{R}{\Sigma' k} = \frac{R}{\Sigma k - k_x}$$

Therefore

$$45 \quad E_{ox} = E_x \frac{\frac{R}{\Sigma k - k_x}}{\frac{R}{k_x} + \frac{R}{\Sigma k - k_x}} = E_x \frac{k_x}{\Sigma k}$$

Suppose now in designing the previous organ with six partials and two manuals we let

$$50 \quad \begin{aligned} k_1 &= k_2 = 4 \\ k_3 &= k_4 = k_5 = k_6 = k_7 = k_8 = 2 \\ k_9 &= k_{10} = k_{11} = k_{12} = 1 \end{aligned}$$

Then

$$55 \quad \Sigma k = 4 + 4 + 2 + 2 + 2 + 2 + 2 + 1 + 1 + 1 + 1 = 24$$

$$E_{o1} = E_1 \times \frac{4}{24} = \frac{E_1}{6}$$

and similarly

$$E_{o2} = \frac{E_2}{6}$$

60 Maximum polarizing potential for these partials

$$= \frac{480}{6} = 80 \text{ volts}$$

65 Let these be fundamentals for the two manuals. Similarly,

$$E_{o3} = E_3 \times 2 \frac{2}{24} = \frac{E_3}{12}$$

$$70 \quad E_{o4} = \frac{E_4}{12}$$

$$E_{o5} = \frac{E_5}{12}$$

Maximum polarizing potential for these partials

$$= \frac{480}{12} = 40 \text{ volts}$$

These could be 2nd, 3rd and 4th harmonics for 5 the two manuals—six partials in all.

$$E_{o6} = E_6 \times \frac{1}{24}$$

$$E_{o10} = \frac{E_{10}}{24}$$

$$E_{o11} = \frac{E_{11}}{24}$$

$$E_{o12} = \frac{E_{12}}{24}$$

10

15

Maximum polarizing potential for these partials

$$= \frac{480}{24} = 20 \text{ volts}$$

20

These could be 5th and 6th harmonics for the two manuals.

Dropping the numerical example again temporarily, we proceed to prove that the system is 25 additive. From Fig. 3

$$E_o = \Sigma' i_m \times \frac{R}{\Sigma' k_m}$$

$$E_m = E_o + R_m i_m$$

$$= E_o + \frac{R i_m}{k_m}$$

$$k_m E_m = k_m E_o + R i_m$$

30

35

where i_m = current in any resistor R_m not connected to zero potential. i_m is positive if $E_m > E_o$ and negative if $E_m < E_o$.

An equation like this can be set up for each resistor connected to potential above ground. 40 Adding all these equations

$$\Sigma' k_m E_m = E_o \Sigma' k_m + R \Sigma' i_m; \text{ but } R \Sigma' i_m = \Sigma' k_m E_o$$

$$\therefore \Sigma' k_m E_m = E_o [\Sigma' k_m + \Sigma' k_m] = \Sigma k E_o$$

$$E_o = \frac{\Sigma' k_m E_m}{\Sigma k} = \Sigma' \left[\frac{k_m E_m}{\Sigma k} \right] = \Sigma' E_{ox}$$

45

The additive condition is then satisfied.

It may be noted that the foregoing proofs are only valid when at least one resistor is connected to ground potential, as otherwise the equations involve a fraction with zero denominator. It is, however, easy to show by the use of the theory of limits that the additive condition still holds when all resistors are connected to other potentials. Suppose we add a resistor which is to be always connected from the generator input terminal to ground. Let this resistor be

$$R_s = \frac{R}{k_s}$$

50

and do not consider it in the summations. Then

$$E_o = \Sigma' \left[\frac{k_m E_m}{k_s + \Sigma k} \right]$$

55

as k_s approaches 0, E_o approaches

$$\Sigma' \left[\frac{k_m E_m}{\Sigma k} \right]$$

This shows that the previous result holds even 70 when the lone resistor to ground is made infinite—i. e., disconnected entirely.

The numerical example already given under Case II may be accepted as illustrative of what may be accomplished by graduating the resistors,

75

as far as the generators near the center of the range are concerned. In an instrument comprising a wide range of pitch this will include the majority of the generators. It will be observed that when a generator is used as fundamental, one-sixth of the potential of the fundamental bus is applied to the generator. When it is used as second, third, or fourth harmonic, one-twelfth of the potential of the corresponding bus is applied to the generator. When it is used as fifth or sixth harmonic, one twenty-fourth of the bus potential is applied to the generator. These fractions will have to be taken into account when the various timbres are set up. The apparent loss of voltage is due to the fact that reserve potential must be available for raising the potential further and further as more and more partials are added. In fact, a little thought is sufficient to show the truth of the following, which might be called first law of additive system. The total potential available must be equal to the sum of the maximum potentials of all partials.

The generators near the ends of the ranges supply a less number of harmonics than those near the middle, and these have to be given special consideration. The fact that it is rather easy to solve the problems which naturally arise in a synthetic instrument from this cause is one of the advantages of my system. The generators of the lowest octave are used as fundamentals only, those of the next lowest octave for fundamentals and second harmonics only, those of the lower half of the third octave for fundamentals, second and third harmonics only, etc. It will be found that if a dummy resistor, of resistance equal to $R/16$, be connected from the input terminal of each generator in the lowest octave to ground, the applied voltage for each of these generators will be the same as that on all other fundamentals. However, as the ear is much less sensitive to the very low frequencies, it will probably prove advisable to increase the resistance of these dummy resistors in order to facilitate equalizing the loudness.

At the other end of the scale, it would be desirable to get along without any generators which are used as harmonics only. But if this is done without making proper compensation, when a timbre rich in high harmonics is being used, an abrupt change of quality and volume will be likely to occur near the top of the scale. Two modifications are possible under the system of my invention. One is the substitution method which has been previously proposed—i. e. when a harmonic turns up missing, a switch and a resistor are provided for it just as though the generator were present. The generator end of this resistor is connected to the input terminal of the fundamental generator, thus substituting an equal amount of fundamental for the missing harmonic. The quality will thus change by steps, but the effective value of the output will remain unchanged regardless of the wave form. My method is to gradually reduce the constants of the harmonic resistors as the upper end of the range is reached. The quality can thus be made to become simpler gradually, as it does in acoustic instruments.

If the keying resistors are large with respect to the internal resistance of the source, there will be no mutual interference between the input circuits of different generators, or the various branch circuits of the same generator, the resistance of the high potential portion of any voltage divider being included in the internal re-

sistance of the source of potential. This fact makes combining the individual generators into a complete instrument relatively easy. It is merely necessary to equip the various switches with mechanical linkages to the proper keys, and connect the switch contacts to the appropriate potential busses. The busses, of course, are equipped with means for adjusting their potential.

There are two general methods for connecting the switch contacts. One method consists in connecting all the live switch contacts which pertain to the same harmonic to the same potential bus. This system is illustrated in the upper manual of the circuit of Figs. 4, 4a and 4b. The other system, which will be explained in due course, is illustrated in Fig. 5. A compromise method for connecting the switch contacts is illustrated in the lower manual of Figs. 4, 4a, and 4b.

Another difficulty with present instruments arises from the fact that substantially all of the truly synthetic instruments employ a separate key-contactor and amplitude control circuit for each partial of each note employed such as represented in Patent 1,956,350 to Laurens Hammond, April 24, 1934; Patent 2,055,719 to Raymond C. Fisher, September 29, 1936; and Patent 1,749,685 to Raymond Zouckermann, March 4, 1930. While a considerable change in harmonics content may not be appreciable to the ear, a large number of harmonics are determining factors in the timbres of various instruments. On this account, it is difficult for the designers of present types of instruments to provide for a sufficient number of harmonics with a reasonable number of parts. Having provided for as many harmonics as are practical, they find themselves confronted with a degree of complexity which permits much finer control of harmonic content than there is any use for, and at the same time a number of harmonics that is not as great as desired.

I alleviate this difficulty by dividing the harmonics into related groups, each group to be controlled by a single key-contactor. The amplitude relations between the members of a group are fixed for each instrument, by adjusting the relative values of the resistors analogous to R_1 , R_2 , R_3 , R_4 , and R_5 of Fig. 1. The relative amplitudes within the group are chosen by experiment, using the known harmonic contents of a large number of instruments as a guide. The controls available to the operator control the amplitudes of entire groups, and thus have a much greater effect on the timbre than controls which affect a single harmonic. The groups could be selected according to the following principles, or in any other way that seemed desirable to the designer of a specific instrument.

Harmonics which bear an octave relationship to each other affect the timbre similarly. Further, it is apparent that harmonics which correspond to notes which form a simple pleasing chord with the fundamental should bear some similarity in their effects on the timbre, though the similarity should not be as great as in the case of the octave relationship. And finally, harmonics corresponding to notes which are dissonant to the fundamental would be quite otherwise, having an important and rather individual effect, probably tending towards harshness in the final quality, but extremely useful musically if only for variety. This feature is illustrated in Manual I of Figs. 4, 4a and 4b.

Another feature of acoustical musical instru-

ments is the fact that the harmonic content is different for different pitches. This has often been considered a defect; on the contrary it is more likely that it is an essential requirement of an instrument which is to be musically satisfying for general use over a long period of time. It is a well-known fact that a change in harmonic content is more obvious to the ear than the mere presence or absence of certain components, so that variation in wave-form with pitch is important in producing variety. This effect is the reason for the musical usefulness of such devices as repeating a passage an octave higher or lower.

Certain musical tones are chiefly characterized by a dependence of the amplitudes of their components on frequency rather than on the harmonic order. Typical tones of this class are the tones of the human voice, the violin and similar stringed instruments, and the tones of the woodwind instruments. These tones are all characterized by the existence of certain bands of frequencies, called formants. Regardless of the pitch of the fundamental of the note emitted the high-amplitude components always lie within a formant band. An exception of course exists when the fundamental is above the highest formant; in this case the note is invariably low in harmonic content.

My system lends itself very readily to quality control by this system. For example, in Figs. 4-4a-4b the resistive leads 201-206 to the polarizing plates 13 could be led back to a common potential. This would permit the use of a single-contact key for however many partials were used. The harmonic content of the originally-generated wave would then be fixed by the values of the individual resistors, which would be seldom, if ever, changed. Quality control would be effected ordinarily by one of two alternative systems. One method would be to use a set of multiple band-pass filters in the amplifier. These filters would be interchangeable by means of quality-control switches operable from the console, or the same filter would be modified by said switches; in which cases the filter elements (inductances, capacities, and resistances) would be adjustable by means of tap-switches or otherwise. Another method would be to connect the output plates 15 of the individual generators, singly or in groups of adjacent pitches, to the amplifier through individual attenuators. The second method would perhaps give more positive control of the quality, but would be more expensive and more complex. In the present state of the art, the characteristics obtainable by filters are almost unlimited, particularly if regenerative vacuum tube circuits or electro-mechanical filter devices are employed. Taken by and large, then, it would seem that the filter method is preferable. Fig. 5 shows the connections for the key-switches and generators when using this system. Fig. 5a shows the associated timbre-control circuits using individual attenuators; Fig. 6 shows an alternative timbre-control scheme using interchangeable filters.

This system, which may be called a pure formant system of quality control, is very attractive from the viewpoint of simplicity of construction, but has certain drawbacks. In the first place, the generators used in this manner cannot be employed in the ordinary harmonic-order control circuit. That is, while the generators and the basic generating circuit is the same in both cases, the quality-control circuits are so different that the two systems described cannot be employed alternatively in the same instrument,

at least not without an almost prohibitively complex switching system. In the second place, it will be noted that the acoustic instruments functioning on the formant system are solo instruments, in the sense that only one note at a time is produced. (In the case of the violin, two notes can be sounded simultaneously, but they will be close together in pitch.) Thus, the volume discrepancies that might otherwise arise are taken care of by the operator, note by note. In the case of a keyboard instrument, where several notes remote from each other in pitch are often sounded simultaneously, a difficulty would arise. It is not known at present how serious this difficulty would be. In any case, the difficulty can be overcome by using a volume limiting tube such as element 342 of Figs. 5a and 6 and explained below.

I have devised a circuit which eliminates these difficulties at the expense of employing a key-controlled switch for each harmonic. This circuit is similar to the circuit previously described, except that the voltage tap to which the individual resistors are connected depends upon the pitch (frequency) of the generator instead of the order of harmonic as in the previous case. This system consists in dividing the generators into groups, the generators in each group comprising a series of adjacent pitches. All live switch contacts in the group, regardless of harmonic number, are connected to the same potential bus. A circuit of this type is illustrated in manual II of Fig. 4a. This may be called a compromise or semi-formant system.

In Fig. 1 the electrostatic generator assembly is indicated at G and is similar to the structure set forth in my Letters Patent 2,001,708, dated May 21, 1935. The control contactors are indicated at K₁, K₂, K₃, K₄, and K₅ having sets of opposite coacting contacts as shown. The control contactors K₁, K₂, K₃, K₄, and K₅, etc., are each operated by a different key. The means for co-ordinating the movement of the contactors are indicated schematically by dotted lines 1. The connections to the source 2 from the coacting contacts of the contactors are indicated at 1a, 2a, 3a, 4a, and 5a. Reference character 3 designates a volume determining resistor between the generator G and the input of the electron tube amplifier 4. Quasi-linear properties may be imparted to generator G through coupling circuit constituted by condenser C and resistances 3 and 5 whereby the impedance of the generator and the input of the amplifier are properly related for obtaining proportionality between active plate area and amplifier input potential, as explained in my Patent 2,001,708. Amplifier 4 has a suitable cathode heating supply as indicated at 6 and a suitable plate circuit supply shown at 7. The output transformer 8 in the output of amplifier 4 connects to a suitable sound reproducer indicated at 9. Condenser 18 produces gradual attack and decay of tones by the method disclosed in Floyd A. Firestone Patent 1,953,753, granted April 3, 1934.

In Fig. 2, I have shown a circuit equivalent to Fig. 1 for a generator producing a single partial according to the mathematical demonstration supra. Like reference characters refer to similar parts described in connection with Fig. 1.

In Fig. 3, I have shown circuits similar to Figs. 1 and 2 using similar reference characters to designate similar parts and showing an equivalent circuit when several partials of different amplitudes are produced simultaneously.

The circuit connections for a two-manual organ constructed in accordance with my invention are shown schematically in Figs. 4—4a—4b. Figs. 4—4a and 4b are continuations of one circuit. The location of parts in the figures is not intended to suggest the location in the actual instrument, but was intended merely to facilitate drawing in the electrical connections, as is usual in schematic circuit diagrams. No attempt has been made to show all the apparatus in the instrument nor all the connections, as it was felt that the principles to be followed could be more readily understood if too great repetition of parts and circuits was avoided.

In Fig. 4, each of elements 13 represents one stator plate of a varying-capacity generator, each of elements 15 the other stator plate, and 14 the intervening rotor plate. The generators have additional designations comprising letters with subscripts. These show the note of the musical scale which the generator emits when used as fundamental. Thus C₁ indicated C in the lowest octave, E₄, E in the fourth octave counting from the bottom, etc. Elements 16 represent individual "voicing" resistors, i. e., resistors for adjusting all notes to the same loudness. Each output plate 15 connects through a voicing resistor 16 and conductor 31 to the grid electrode of amplifier tube 34 in Fig. 4b.

Elements 101 to 112 and 201 to 206 are the individual harmonic-control resistors analogous to those shown at R₁—R₆ in Figs. 1 to 3. In these designations, the first digit gives the manual and the last two digits the order of the harmonic with which the resistor is associated. Thus a 101 resistor would control a fundamental tone of manual I, a 205 resistor a fifth harmonic of manual II, etc.

Each of these resistors has one terminal connected to an input plate 13, and the other terminal connected to the movable contact of a key-controlled switch 19. All of the resistors connected to each of the generators shown are represented. As not all of the key-controlled switches are shown, the connections to one terminal of many resistors 101—112, 201—206 had to be omitted. It is to be understood that in the actual instrument each of these terminals is to be connected to the movable contact of the appropriate key-controlled switch.

A plurality of switches 19 are controlled by each playing key. In accordance with the convention used in radio for showing a gang-switch, gang-condenser and the like, the mechanical linkages whereby the playing keys operate these switches are represented by dotted lines. Linkages designated with the numeral 1 are operated by playing keys of manual I; linkages designated with the numeral 2 are operated by playing keys of manual II. These linkages are further designated by letters with subscripts which identify the playing key which actuates them. Thus 1C₁ indicates the lowest C of the first manual, 2G₁ the lowest G of the second manual, etc.

Each of switches 19 has three contacts, a movable contact, and two fixed contacts. The fixed contact which is in use when the key is in the non-playing position (up) is connected to ground or zero potential through conductor 30 in all cases. The other fixed contact connects to a suitable steady potential according to the following scheme:

In manual I, control by the harmonic-order system is exemplified, the feature of multiple harmonics per contact being incorporated. Each

101 resistor (i. e., each fundamental) connects through a separate switch 19 to conductor 20, which is supplied with a potential controlled as shown in Fig. 4b, which will be hereinafter explained. The second, fourth, and eighth harmonics being in octave relationship to each other (and the fundamental) are controlled by a single switch 19 as follows. Plate 13 of the generator producing the 2nd harmonic of the note under consideration is connected through a 102 resistor 10 to the movable contact of a switch 19; plate 13 of the fourth harmonic generator is connected to the same point through a 104 resistor, and plate 13 of the eighth harmonic generator to the same point through a 108 resistor. The active contact of this switch 19 is connected to conductor 21, which is supplied with a controlled potential by the circuit shown in Fig. 4b. Now the relative amplitudes of the second, fourth, and eighth harmonics are controlled by the relative resistances of resistors 102, 104 and 108. The amplitude of the group as a whole is controlled by the potential applied to conductor 21. The sixteenth harmonic could be added to this group if desired.

Similarly, the third, sixth, and twelfth harmonic generators are supplied with potential from conductor 22 through a common switch 19. (The frequency of these and succeeding harmonics is of course only approximately correct.) The fifth and tenth harmonic generators are supplied with potential from conductor 23 through another common switch 19. The frequencies so far are all involved in the chord known as the "major triad" in the study of harmony. The readily available dissonant harmonics, the seventh and the ninth, are lumped in the last group, and supplied potential through conductor 24.

It will be noted that this arrangement is in accordance with the principles previously stated. Many variations of the arrangement are possible, some of which may be preferable under certain conditions than the arrangement set forth herein and it will be understood that my disclosure herein is to be considered in the illustrative sense and not as limiting my invention to the specific arrangement shown.

Certain conductors in manual I are shown unterminated, as they lead to apparatus not shown. That is to say the circuits are repetitions of the circuits heretofore described. Thus conductor 120 goes to plate 13 of the D₃ generator (not shown) through a 103 resistor (not shown). Similarly, conductor 121 goes to plate 13 of the B₃ generator through a 105 resistor, and plate 13 of the B₄ generator through a 110 resistor. Conductor 122 goes to plate 13 of the F₄ generator through 107 resistor, and to plate 13 of the A₄ generator through a 109 resistor. Conductor 123 goes to plate 13 of the G₅ generator through a 112 resistor. Conductor 124 goes to plate 13 of the E₅ generator through a 110 resistor. Conductor 125 goes to plate 13 of the D₅ generator through a 109 resistor. Conductor 126 goes to plate 13 of the A₅ generator through a 104 resistor and to plate 13 of the A₆ generator through a 108 resistor. Conductor 127 goes to plate 13 of the A₅ generator through a 106 resistor and to plate 13 of the A₆ generator through a 112 resistor. Conductor 128 goes to plate 13 of the A₅ generator through a 108 resistor. Conductor 129 goes to plate 13 of the A₅ generator through a 110 resistor. Conductor 130 goes to plate 13 of the A₅ generator through a 112 resistor. Conductor 131 goes to plate 13 of

the A₂ generator through a 102 resistor. Conductor 132 goes to plate 13 of the F₄ generator through a 101 resistor. Conductor 133 goes to plate 13 of the A₂ generator through a 103 resistor.

Reference character 50 is a three-position multi-gang switch. When thrown to the position farthest to the left on contact 53 it associates a large condenser 51 with resistors 101 to 110, so as to produce a very gradual attack and decay, in a manner explained by Firestone (loc. cit.). When switch 50 is placed in the center position on contact 54, a smaller condenser 52 is substituted, giving a less gradual attack. When switch 50 is placed in the position to the extreme right on contact 55 the condensers are disconnected and an abrupt attack results.

Manual II is connected on the compromise or semi-formant system. Aside from the number of 20 harmonic-control resistors and key-controlled contactors, the only difference in the circuits of manual I and manual II is in the connections from the fixed contacts of the switches 19 to the source of potential. Thus the high-potential 25 fixed contacts of such of the switches 19 as control fundamental components are connected to conductor 40. The corresponding contacts of all other switches 19 which connect to generators in the second octave connect to conductor 41, those 30 associated with generators in the lower half of the third octave connect to conductors 42, 43, 44, 45, etc.

In Fig. 4b, 34 is an amplifier tube supplied with energy from the generators through conductor 31 and volume control 32. Volume control 32 should be operable from the console, preferably by means of a foot pedal. Vacuum tube 34 feeds loudspeaker 36 through an intervening vacuum-tube system typified by tube 35.

40 Numeral 140 designates the mechanical linkage of a multiple switch which may be called an adjustable-quality tappet. When this tappet is depressed, individual switches 141 render adjustable potential dividers 142 effective in controlling the 45 potential of conductors 10-14. Potential dividers 142 obtain their electrical energy from common source of potential 36.

50 Numerals 150 and 160 designate the mechanical linkages of multiple switches which may be called fixed-quality tappets. With tappet 140 raised, depressing 150 or 160 forms a potential divider of which the upper leg is resistor 152 or 162 and the lower leg is resistor 135. The value of resistors 152 control the potentials impressed on conductors 10-14 when tappet 150 is depressed. Similarly another tone quality, depending upon the 55 values of resistors 162, results from depressing tappet 160. Tappets 150 and 160 may be depressed simultaneously, in which case the amplitude of each individual harmonic is greater than it would be with only one tappet depressed, but not as great as the sum of the individual amplitudes. Tappet 140 can be operated simultaneously with one or more fixed-quality tappets, in which case it functions as an adjustment on the quality already set up by the fixed-quality tappet. The amplitude of any given harmonic may be increased or decreased, depending upon the 70 relation between the original amplitude of the harmonic and the setting of the corresponding adjustable potential divider 142. The magnitude of this effect depends upon the magnitude of resistors 143, being larger when 143 is smaller.

75 Additional fixed-quality tappets similar to 150

and 160 can be added as desired. A truly additive circuit for the tappets can readily be worked out along the lines previously given for the generators; but as such a circuit would require more polarizing voltage and would be more complex to design and construct, it is believed that the circuit given is preferable.

Numerals 250 and 260 designate the mechanical linkages for fixed-quality tappets for the second manual. They function in the same manner 10 as the tappets for the first manual. An adjustable-quality tappet could be added along previous lines, but under the formant system there does not seem to be a great deal of point in doing this.

In Figs. 5 and 5a the circuit connections for 15 the pure formant scheme of quality control, using only one contact per playing key, are shown. Figs. 5-5a are drawn as though there were only three notes per octave and four octaves in the 20 complete instrument; this is for the sake of simplicity only, and it is to be understood that the arrangement may be readily extended to the regulation twelve semitones per octave and as many octaves as desired. Again for the sake of simplicity, only three harmonics are shown. The individual harmonic control resistors are 301 for the fundamental, 302 for the second harmonic, and 303 for the fourth harmonic, the third not being used in the illustration. These resistors are shown variable, and are ganged together by the 30 mechanical linkages 304, 305, and 306 respectively. This constitutes an optional auxiliary quality control. For reasons of expense, this would in practice probably be accomplished by resistors with one or two taps and a gang switch, as a 35 large number of resistors have to be controlled if this feature is to be included. The 302 and 303 resistors are at all times to be graduated so that the resistors for the highest notes have the highest value of resistance, to avoid sudden changes 40 in quality, as previously explained.

By tracing out the circuit, it will be noted that each of the playing keys 300 which control notes in the highest octave (last three notes on the right of the diagram) connects plate 15 of one of the generators to potential source 308 through a 301 resistor. This is the only connection made in sounding a note of the highest octave, there being no harmonic generators above the fundamental range, as previously explained, so that the 45 notes of the highest octave are substantially pure sine waves—a condition which is approximated by many instruments. The playing keys of the next highest octave each connect plate 15 of one generator to source 308 through a 301 resistor, and plate 15 of another generator to source 308 through a 302 resistor. The notes in this octave 50 therefore contain fundamental and second harmonic components only.

Each of the stator plates 13 of the generators is connected through a 307 resistor to one of the conductors 310-314. Resistors 307 simultaneously function as voicing resistors, and to prevent "cross-talk" and "robbing." (If the generators 65 are properly designed—i. e. with the variable part of the capacity small with respect to the fixed part, there should be little trouble with cross-talk anyway.) The three lowest pitched generators connect to conductor 310, the next two to 70 conductor 311, etc. Conductors 310 to 314 connect individually to fixed quality-control tappet 320 and adjustable quality-control tappet 330. Thence the potentials from the various groups of generators, each now having its appropriate am- 75

plitude as set by resistors 321 and/or 331, is applied to the input circuit of amplifier tube 340. The output circuit of tube 340 contains transformer 341, whose secondary is wound for push-pull operation. Connected to this push-pull secondary is double diode tube 342, which functions as an automatic volume limiting device to prevent sudden burst of sound in case a note having a strong partial in a band which is little attenuated by resistors 321 or 331 is sounded. The cathode of double diode 342 is given an adjustable positive bias through resistor 348. As long as the audio frequency potential across the secondary winding of transformer 341 is insufficient to raise the potential of the diode plates above the potential of the cathode at any time, the diode remains inoperative. But if the peaks of the audio frequency potential are sufficiently large, the diode will draw current, thus shunting the transformer secondary and reducing its efficiency as a coupling device.

The audio frequency potential, as limited by this device, is thence transmitted to volume control 343, which is operated manually or by a foot pedal. After further amplification, it is then transmitted to loud-speaker 347.

Figure 6 gives an alternative method of quality control. Conductors 310-314, instead of being connected individually to tappet-controlled switches, are all connected together to the amplifier input circuit. The amplifier is then provided with a number of wave-filters, arranged to be employed alternatively. In Fig. 6, a gang-switch comprising individual multi-point switches 390a and 390b mechanically linked together, is employed for selecting the wave-filters. Three different types of filters have been shown. No importance is to be attached to the precise circuits of these filters; they are intended to be typical of the numberless circuits known to the art which will provide band-pass or multiple band-pass characteristics. The network 360 is a fairly common type of band-pass filter employing three inductances and three capacities. Voltage divider 352, amplifier 350, regeneration-control vario-coupler 351, tuned circuits 353, choke coil 354 and blocking condenser 355 comprise a filter with band-pass characteristics sharpened by regenerative means. The third interchangeable filter is a magneto-striction type adapted from a filter circuit employing piezo-electric elements. Magnetostrictive rod 380 is wound with a (multi-layer) helical coil 381 having center tap 382 connected through condenser 383 and tuned-circuit 384 back to ground.

I have no intention of making any claims on these filters per se, neither as to originality nor as to the operability of the exact circuit shown. I do, however, maintain that filter circuits designed along the general lines shown are well known in the art and can be made to fulfill a wide variety of frequency-response conditions; and that such filters, used in combination with generating and keying circuits substantially as here disclosed, constitute a new and useful device for producing music.

While I have described my invention, therefore, in certain preferred embodiments, I intend no limitations thereby upon my invention; and I desire it to be understood that modifications may be made and various devices other than those specified may be employed within the scope of the appended claims.

What I claim as new and desire to secure by Letters Patent of the United States is as follows:

1. In an electrical musical instrument including a multiplicity of playing keys controlling a multiplicity of electric alternators and an electric sound producer controlled by said alternators, the combination of a pair of input terminals for each alternator, one or more switches operated by each of said playing keys, each of said switches comprising a pair of fixed contacts and a movable contact controlled by means of said keys, electrical circuit connections including one of said input terminals from each of said alternators and one of said fixed contacts from each of said switches connected to a common point, a source of potential connected to said common point, a plurality of conductors connected to said source of potential through adjustable potential dividers, a connection from each remaining fixed contact of said switches to some one of said conductors, and resistive connections from each movable contact of said switches to one or more of the remaining input terminals of said alternators such that the timbre changes progressively with pitch. 5 10 15 20

2. In an electrical musical instrument including a multiplicity of playing keys controlling a multiplicity of electric alternators and an electric sound producer controlled by said alternators, the combination of a pair of input terminals for each alternator, one or more switches operated by each of said playing keys, each of said switches comprising a pair of fixed contacts and a movable contact controlled by means of said keys, electrical circuit connections including one of said input terminals from each of said alternators and one of said fixed contacts from each of said switches connected to a common point, a source of potential connected to said common point, a plurality of conductors connected to said source of potential through adjustable potential dividers, a connection from each remaining fixed contact 40 of said switches to some one of said conductors, and resistive connections from each movable contact of said switches to one or more of the remaining input terminals of said alternators, the contacts of said switches which are connected to any one of said conductors all being associated with the same alternator or with alternators productive of adjacent pitches. 45

3. In an electrical musical instrument, the combination as set forth in claim 1, with means for selecting the potential conductor to which certain of said remaining fixed contacts are connected on the basis of pitch, and means for selecting the potential conductor to which the balance of said remaining fixed contacts are connected on the basis of harmonic order. 50 55

4. In an electrical musical instrument including a plurality of alternators productive of different musical frequencies, and a sound reproducer, the combination of input and output circuits for said alternators, key-controlled contactors in said input circuits for rendering said alternators effective upon said sound reproducer, and resistive electrical connections from each key-controlled contactor to certain selected alternators, the frequencies of said selected alternators being so related that when each of the corresponding notes is sounded simultaneously with the lowest-pitched of them, the resulting chords are simple ones which are similar to each other or at least closely related to each other, the simplicity and the relatedness of said chords being decided according to the teachings of the musical art of harmony. 60 65 70

5. In an electrical musical instrument includ-

ing a multiplicity of contactors operated by playing keys, each key controlling a single contactor, a multiplicity of alternators having input and output terminals, a source of potential, and an electrical sound-producing device the combination of electrical connections between the input terminals of said alternators, said contactors and said source of potential for supplying the input terminals of more than one of said alternators with electrical energy from said source of potential when one of said playing keys is depressed, and a plurality of amplitude control circuits connected to said input terminals of said alternators, said control circuits being so arranged that the resultant amplitude of any one component of a musical note is a predetermined function of its pitch.

6. In an electrical musical instrument including a multiplicity of contactors operated by playing keys, a multiplicity of alternators having input and output terminals, a source of potential, and an electrical sound-producing device the combination of electrical connections between the input terminals of said alternators, said contactors and said source of potential for supplying the input terminals of more than one of said alternators with electrical energy from said source of potential when one of said playing keys is depressed, and a plurality of amplitude control circuits connected to said input terminals of said alternators, each of said control circuits being individual to one frequency or common to a band of adjacent frequencies.

7. In an electrical musical instrument including a multiplicity of contactors operated by playing keys, a multiplicity of alternators having input and output terminals, a source of potential, and an electrical sound-producing device the combination of electrical connections between the input terminals of said alternators, said contactors and said source of potential for supplying the input terminals of more than one of said alternators with electrical energy from said source of potential when one of said playing keys is depressed, a plurality of amplitude control circuits connected to said input terminals of said alternators, each of said control circuits being individual to one frequency or common to a band of adjacent frequencies, and means for variably adjusting each of said control circuits.

8. In an electrical musical instrument, the circuit connections as defined by claim 1, with the magnitude of the resistances of the individual resistive connections therein described being graduated so that the relative amplitudes

of the partial tones will change from note to note in a musically pleasing manner.

9. In an electrical musical instrument including a plurality of electric alternators operating at different frequencies, an electric sound producer and playing keys for rendering frequencies produced by the alternators effective in the sound producer, in combination with input and output terminals for said alternators, a source of potential connected in common with one input terminal of each alternator, and individual means energized at different potentials from said source and connected with selected alternators at the remaining input terminals thereof for providing tone partials of different amplitudes at the various frequencies; the output terminals of said alternators being connected in common with the electric sound producer, each of the playing keys being arranged for sounding selected partials simultaneously in the sound producer, and the total potential available at said output terminals being substantially equal to the sum of the maximum potentials of all the partials sounded, regardless of the number of playing keys operated.

10. In an electrical musical instrument, the combination set forth in claim 9 wherein said individual means comprise resistors of equal value whereby the amplitudes of the partials produced are proportional to the different potentials at said source.

11. In an electrical musical instrument, the combination set forth in claim 9 wherein said individual means comprise resistors of unequal value whereby the amplitudes of the partials produced may be selectively determined in relation to the different potentials at said source.

12. In an electrical musical instrument including a plurality of electric alternators operating at different frequencies, an electric sound producer and playing keys for rendering frequencies produced by the alternators effective in the sound producer, in combination with input and output terminals for said alternators, a source of potential connected in common with one input terminal of each alternator, and individual means connected from said source to selected alternators at the remaining input terminals thereof for providing tone partials of different amplitudes at the various frequencies; the output terminals of said alternators being connected in common with the electric sound producer, with the total potential available at said output terminals being substantially equal to the sum of the maximum potentials of all the partials sounded.

WESTLEY F. CURTIS.
